US00D953989S

(12) **United States Design Patent** (10) **Patent No.:** **US D953,989 S**
Egawa (45) **Date of Patent:** **** Jun. 7, 2022**

(54) **CONNECTOR**(71) Applicant: **Molex, LLC**, Lisle, IL (US)(72) Inventor: **Toyokazu Egawa**, Yamato (JP)(73) Assignee: **Molex, LLC**, Lisle, IL (US)(***) Term: **15 Years**(21) Appl. No.: **29/706,758**(22) Filed: **Sep. 24, 2019**(30) **Foreign Application Priority Data**

Mar. 26, 2019 (JP) 2019-006403

(51) **LOC (13) Cl.** ..... **28-03**(52) **U.S. Cl.**USPC ..... **D13/133; D13/151**(58) **Field of Classification Search**

Assistant Examiner — Landon Thomas Cassell

(57) **CLAIM**

The ornamental design for a connector, as shown and described.

DESCRIPTION

FIG. 1 is a perspective view of connector showing our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is a perspective view thereof in use.

The broken lines in the drawings depict portions of the connector that do not form a part of the claimed design.
